(57) **CLAIM**

We claim the ornamental design for an arrow insert and collar, as shown and described.

DESCRIPTION

FIG. 1 is a top front right side isometric view of an arrow insert and collar showing our new design.

FIG. 2 is a top front right side isometric exploded view thereof;

FIG. 3 is a top front right side isometric view thereof;

FIG. 4 is a bottom rear left side perspective view thereof;

FIG. 5 is a front view thereof;

FIG. 6 is a rear view thereof;

FIG. 7 is a left side view thereof; the top view being identical thereto;

FIG. 8 is a right side view thereof; the bottom view being identical thereto;

FIG. 9 is a cross-sectional view thereof, taken along line 9-9 shown in FIG. 5.

FIG. 10 is a top front right side isometric view of the arrow insert;

FIG. 11 is a bottom rear left side perspective view of the arrow insert;

FIG. 12 is a front view of the arrow insert;

FIG. 13 is a rear view of the arrow insert;

FIG. 14 is a left side view of the arrow insert, the top view being identical thereto;

FIG. 15 is a right side view of the arrow insert, the bottom view being identical thereto;

FIG. 16 is a top front right side isometric view of the collar;

FIG. 17 is a bottom rear left side perspective view of the collar;

FIG. 18 is a front view of the collar;

FIG. 19 is a rear view of the collar;

FIG. 20 is a left side view of the collar, the top view being identical thereto; and,

FIG. 21 is a right side view of the collar, the bottom view being identical thereto.

The broken lines in the figures illustrate an environment of the arrow insert and collar that form no part of the claimed design.
